UNITED STATES PATENT OFFICE.

GUSTAVE LARSON, OF BUENOS AIRES, ARGENTINA.

CROSS-HUNG SELF-BALANCING SLUICE OR VALVE GATE.

1,075,428.

Specification of Letters Patent.

Patented Oct. 14, 1913.

Application filed March 23, 1912. Serial No. 685,830.

To all whom it may concern:

Be it known that I, GUSTAVE LARSON, a subject of the Kingdom of Sweden, residing in the city of Buenos Aires, Argentina, have invented a new and useful Cross-Hung Self-Balancing Sluice or Valve Gate, of which the following is a specification.

This invention refers to automatic sluice gates of the kind which open by the pressure 10 of the water or liquid and close by their own gravity.

Automatic sluice gates such as have been utilized heretofore have generally been of a somewhat cumbersome and expensive construction, and the object of the present invention is to provide a simple, durable, efficient and economical device of this character which may be applied for the purpose of causing the sluice gate to open and allow 20 the water to flow freely when the latter reaches a certain predetermined level or height, and to close when it falls below such level or height, both operations being automatically effected without any attention 25 whatever.

Another object of the invention is that of providing an automatic valve or gate which shall open automatically to allow the water to flow freely in one direction, and close so 30 as to prevent the flow of the water in the other direction, the principle of the hanging of gates for the two uses being identical, the sole variation being a change in the points of support.

With these and other objects in view, the invention consists of certain novel features of construction and combinations of parts which will be hereinafter more fully described and pointed out in the claims.

In the accompanying drawings, in which like characters represent like parts in all the figures:—Figure 1— is a diagram showing the preferred manner of connecting the gate in order that it will open automatically for 40 a given water level and close for a slightly lower level, both hanging rods being on the down-stream side of the gate. Fig. 2— is a similar view of a gate mounted for the same purpose as that shown in Fig. 1, but with 45 the base pivot blocks of the bars adjustably mounted on arcuate guideways so that the relative position of the connecting bars may be changed to suit conditions. Fig. 3— shows the preferred form of mounting the 50 gate for permitting the flow in one direction but not in the other. Fig. 4 shows a modi-

fied form of mounting the gate for the same purpose as that shown in Fig. 1, one connecting bar being disposed on the down stream side of the gate and the other connecting bar on the up-stream side. The arrow indicates the direction of flow, and the gate and rods, when the gate is open, assume the position shown in the dotted lines. Fig. 5 shows another modified form of arranging 60 the connecting bars in mounting the gate for the same purpose as that shown in Fig. 1, the arrow indicating the direction of flow of the water, and the gate and rods when open assume the position shown by the dotted 65 lines. Fig. 6 shows another modified form of mounting the gate for the same purpose as that shown in Fig. 1. In this modification both rods have their base pivot blocks mounted on the down stream side in an over- 70 head position. When the gate is open the rods and gate assume the positions indicated by the dotted lines. The direction of flow of the water is indicated by the arrow. Fig. 7 shows a modified form of mounting the gate 75 for the same purpose as that shown in Fig. 3, the connecting bars being arranged on opposite sides of the gate. The open position of the gate is indicated by the dotted lines and the normal direction of flow of the 80 water is indicated by the arrow. Fig. 8 shows a modified form of mounting the gate for the same purpose as that shown in Fig. 3 but having the connecting bars arranged on opposite sides of the gate and the base 85 pivot block of one bar mounted overhead and the base pivot block of the other bar mounted below. The gate when open assumes the position shown by the dotted lines. The normal direction of flow is indicated by 90 the arrow. Fig. 9— is an elevation of the dam, looking from the down stream side, and showing the manner of placing several sets of hangings in the simplest form. Fig. 10— is a similar view showing the manner 95 of making one of the connecting or supporting rods in the form of an angular brace.

Referring to Fig. 1, in which the effect to be produced, as above stated, is that of opening the gate at a given level and closing it at 100 a slightly lower level, A represents the gate, B a fixed pivotal point on the floor for one of the rods; D a fixed pivotal point on the floor for the other rod of the set; E and C the pivotal points on the gate, the rods, 105 therefore, being respectively represented by the expressions B—C, and D—E. The rod

B—C swings on the pivot B and the rod D—E on the pivot D. When the rod B—C swings, all points on it move in a direction perpendicular to its position, and in like manner in the case of D—E, all points of which move perpendicularly to its temporary position. With F as a center of rotation, E and C also move perpendicularly to D—E and B—C respectively. It, therefore, follows that the crossing point of the rods is always the center of rotation for the gate, the center of gravity of which is at G. The position of the various parts when the gate is closed is represented by full lines and when open by dotted lines. With F, as pole, we obtain:—

$$\text{Closing moment} = (\text{weight of gate}) \times (\text{horizontal projection of } G F);$$

$$\text{Opening moment} = (\text{water pressure}) \times (\text{height of resultant of water pressure above } F).$$

As the gate opens, the center of gravity G of the gate and also the crossing point F of the rods, both move to the right with reference to Fig. 1, but F will always project farther to the right than E, as seen from said figure. Hence the weight will for all possible positions of gate produce a moment tending to close the same. H is a chain for limiting the extent of opening. J is a sill for determining closed position. It is, therefore, evident that the above construction, proportioned and designed for the individual conditions of each case, will operate automatically. The rods may be adjustably mounted as indicated in Fig. 2; that is—the pivotal points can be set in guides K and K' curved to a radius equal to the length of the corresponding rod, thus allowing adjustment without changing the actual lengths of the connecting bars B—C and E—D, for by sliding the pivot blocks in the curved guides their relative positions and angles may be changed to suit the various conditions under which it may be desired to have the gate open or close.

In the form of construction described above, the advantages obtained are: (1) that no counter-weights are needed; (2) that the gate is held rigidly by the rods; (3) that the supporting points rest above the floor line; (4) that the friction losses are reduced to a minimum, and (5) that the pressure of the water against the gate causes the gate to press tightly against the sill piece, thereby aiding in producing a tight joint.

Referring to Fig. 3—the gate is hung in such a manner that the crossing point of the supporting rods is about level with the top of the gate and only slightly to the right of the vertical center line of gravity of the gate, that distance being marked *m* in this figure. The rods are so designed that *m* is practically constant for all possi-

ble positions of gate, but always to the right, hence the gate is perfectly balanced without the use of counterweights, serving the purpose of permitting the flow of water or other liquid in one direction but preventing the back-flow in the opposite direction, the advantages being the same as in the case of Figs. 1 and 2.

The system of hanging gates herein described may be applied to gates of large dimensions by repeating the number of sets of the devices described. The form of the gate itself is not shown in the drawings, as it may be of any preferred construction, the invention residing purely in the manner of hanging the same.

In the form of construction herein described, which is the preferred one, it is understood that the relative position of the pivotal points may be changed to suit the conditions of each case, and that the invention should be considered liberally as covering any variation which might be produced in the relative positions of the rods and of their pivotal points, such possible variation being practically indefinite. In like manner the form of the rods is subject to variation, as they may either be straight, curved or angular in form, to suit the varying conditions and to reinforce the construction. The supports when suspended from above may also be chains or cables in place of rods.

Having thus described my invention, what is claimed is:—

1. In a sluice gate structure, the combination of a sluice way provided with a gate abutment, a sluice gate, rods on the downstream side of the gate disposed in crossed relation and having their ends pivotally connected with the gate, and pivotal mountings for the remaining ends of the rods adapted to be fixed in a given position, the crossing or point of intersection of said rods being at all times below the center of gravity of said gate, substantially as described.

2. In a sluice gate structure, the combination of a sluice way provided with a gate abutment, a sluice gate, rods on the downstream sides of the gate and disposed in cross relation and having their ends pivotally connected with the gate, and pivotal mountings for the remaining ends of the rods adapted to be fixed in a given position, the crossing or point of intersection of said rods being at all times below the center of gravity, and means for limiting the opening movement of the gate, substantially as described.

3. In a sluice gate structure, the combination of a sluice way provided with a gate abutment, a sluice gate, rods disposed in crossed relation and having their ends pivotally connected with the gate, and pivotal

mountings for the remaining ends of the rods adapted to be fixed in given positions, the crossing or point of intersection of said rods being at all times below the center of gravity of the gate, substantially as described.

In testimony whereof I affix my signature in presence of two witnesses.

GUSTAVE LARSON.
